Des. 212,566
Patented Oct. 29, 1968

212,566

AIR CUSHION VEHICLE

Ralph P. Maloof, Encino, Calif., assignor to Cushion-flight Corporation, San Bernardino, Calif., organized under the laws of California

Filed Oct. 18, 1967, Ser. No. 9,062

Term of patent 14 years

(Cl. D71—1)

Fig. 1.

Fig. 2.

Fig. 3.

FIG. 4.

FIG. 5.

FIG. 6.

FIG. 7.

FIGURE 1 is a perspective view from the front of the air cushion vehicle, showing my new design;

FIGURE 2 is a perspective view thereof from the rear of the vehicle;

FIGURE 3 is a side elevational view thereof;

FIGURE 4 is a top plan view thereof;

FIGURE 5 is a bottom plan view thereof;

FIGURE 6 is a front elevational view thereof; and,

FIGURE 7 is a rear elevational view thereof.

I claim:

The ornamental design for an air cushion vehicle, substantially as shown.
